Primary Examiner — Sheryl Lane*Assistant Examiner* — Ieisha Price(74) *Attorney, Agent, or Firm* — Goudreau Gage Dubuc; Gwendoline Bruneau(57) **CLAIM**

The ornamental design for a snow removal tool, as shown and described.

DESCRIPTION

FIG. 1 is perspective front view of the snow removal tool; FIG. 2 is a perspective rear view of the snow removal tool of FIG. 1;

FIG. 3 is a side view of the snow removal tool of FIG. 1; FIG. 4 is a front view of the snow removal tool of FIG. 1; FIG. 5 is a top view of the snow removal tool of FIG. 1; FIG. 6 is a bottom view of the snow removal tool of FIG. 1; and,

FIG. 7 is a rear view of the snow removal tool of FIG. 1. The broken lines in the drawings illustrate portions of the snow removal tool and form no part of the claimed design.
